UNITED STATES PATENT OFFICE.

ELROY C. ROBERTSON, OF CLEVELAND, OHIO, ASSIGNOR, BY MESNE ASSIGNMENTS, TO ELECTRIC VACUUM CLEANER COMPANY, INC., OF EAST CLEVELAND, OHIO, A CORPORATION OF NEW YORK.

SUCTION-CLEANER.

1,333,682.

Specification of Letters Patent. Patented Mar. 16, 1920.

Application filed May 31, 1917. Serial No. 171,814.

To all whom it may concern:

Be it known that I, ELROY C. ROBERTSON, a subject of the King of Great Britain, and a citizen of the Dominion of Canada, residing at Cleveland, in the county of Cuyahoga and State of Ohio, have invented a certain new and useful Improvement in Suction-Cleaners, of which the following is a full, clear, and exact description, reference being had to the accompanying drawings.

This invention relates to suction cleaners of the type wherein a casing having a collecting nozzle and a motor operated fan is moved about over the floor so as to present said nozzle to various parts thereof to remove dust and refuse therefrom. The objects of the invention are the provision of a device of this character of simplified, improved, and cheapened construction, greater lightness and stability and high operating efficiency; the provision of a new, simplified, and improved brush mechanism; while further objects and advantages will become apparent as the description proceeds. In the drawings, accompanying and forming a part of this application I have illustrated one type of construction in which my invention may be embodied, although it will be clear that many changes could be made therein without departing from the scope of my inventive idea or sacrificing the benefits of my improvements. In these drawings, Figure 1 represents a side elevation of my improved cleaner; Fig. 2 represents a longitudinal vertical sectional view through the nozzle and fan casing, the motor shell being shown in elevation; Figs. 3 and 4 are sectional views corresponding to the lines 3—3 and 4—4 respectively of Fig. 2; Fig. 5 is a sectional view corresponding to the line 5—5 of Fig. 3; Fig. 6 is a detail view of the brush separate from the cleaner; and Fig. 7 a view of the brush casing.

45 Describing the parts for reference characters, 1 represents the outer wall of the fan chamber, the same being of substantially spiral shape, said wall at its portion of maximum radius merging with the outlet neck 2. At its rearward side the fan casing 1, is extended to form the axial cylindrical collar 3 into which fits the end 4 of the

motor shell 5. At the forward side of the fan chamber is formed the collecting nozzle which consists of a convex web 6 extending forwardly and downwardly opposite to and in alinement with the collar 3 and merging with the wall 7 whose direction is transverse to the fan chamber axis and which terminates in a transverse lip 8. Spaced from and substantially parallel to the wall 7 is a second wall 9 terminating in a lip 10 which, in connection with the lip 8, defines an inlet mouth. The plane of this mouth, in the present embodiment, is substantially parallel to the fan chamber axis, and the walls 7 and 9 are approximately perpendicular thereto. The lateral margins of these walls are connected by a web which first rises abruptly, as shown at 11, and then tapers inwardly and upwardly as at 12 until it merges with the web 6 as shown at 13. Beneath and inside of the web 6 is a tubular wall 15 defining a passageway opening into the center of the fan chamber, said passageway also communicating with the space between the walls 7 and 9. I have also shown the wall 15 as connected to the web 12 by an internal stiffening web 16, but this is not necessary structurally. The wall 7 is formed with an aperture 18, in alinement with the fan chamber axis adapted to receive either a removable cover 19 for closing it or a hose tube, (not shown,) extending into the inner opening. The motor shell is secured in the collar 3 by means of a plurality of radial screws 20—20 in the well-known manner.

The suction fan is shown at 24, and in order to form a smooth and close fitting wall for the fan chamber past which the fan blades can sweep closely without binding, I first recess the chamber wall, as shown at 25 and then introduce therein a flat circular steel plate 26. This plate is formed with a central aperture in which is closely received an annular projecting lip 27 formed at the extremity of the tubular wall 15, which lip is afterward spun over so as to secure said plate and hold it permanently in place. The casing is ordinarily cast out of aluminum which generally has a rough and uneven surface, and, owing to its toughness, is very hard to machine. The construction I

have illustrated can all be cast excepting the few narrow bearing places, wherefore the manufacture is much facilitated.

In the embodiment here shown the casing is supported for movement about the floor by means of a single central roller 30 secured to the motor casing at the rear of the center of gravity, together with a pair of rollers 31-31 arranged one at each side of the machine in the rear of the inlet mouth and in front of the center of gravity of the casing. The latter rollers are conveniently journaled upon a crankshaped rockshaft 32 suitably pivoted to the casing and vertically adjustable by means of the set screw 33. The neck 2 communicates with the dust bag 34, and the machine is moved about by means of the handle 35 connected by the curved yoke 36 to pivots 37-37 arranged below and in front of the center of gravity of the casing. The fan chamber is so disposed relatively to the carrying means that the outlet neck rises at one side of the casing, the radius of the fan chamber wall decreasing as it passes beneath the machine until it becomes a minimum at the point adjacent to the opposite side of said outlet neck, at which point said wall approaches closely to the extremities of the fan blades as shown in Fig. 4. This arrangement affords the clearest possible sweep to the refuse discharged from the fan chamber, and produces a more efficient combined interconnection between the force of gravity and the force created by the centrifugal motion of the fan than any other arrangement with which I am familiar.

Any suitable or convenient brush mechanism can be employed in connection with my improved cleaner, the one which I prefer being shown in Figs. 3, 5, and 6. According to this construction the brush consists of a wooden bar 40 having bristle tufts 41 projecting from one edge and a spring 42 projecting from the opposite edge. This bar 45 is inserted longitudinally into a rectangular casing 43 having in one side a longitudinal slot 44 for the protrusion of the bristles. At one end of said casing is an ear 45 having a longitudinal notch and at the opposite end 50 an ear 46 having a transverse notch.

Located inside the collecting nozzle are a pair of spaced studs 47-47 having heads 48-48 and between said heads and the bases of the studs are U shaped friction springs 49. To insert the brush the ear 45 is first presented to its stud so that it may enter between the head 48 and spring 49, after which the brush casing is swung laterally so as to present the ear 46 to the other stud in the same manner. The brush is thus securely held during use but can be instantly removed for the purpose of cleaning or replacement. It will be understood that many changes of detail of construction could be made without

departing from my invention, and all such modifications are claimed as within the purview of my Letters Patent.

Having thus described my invention what I claim is:

1. In a suction cleaner, the combination of a fan casing, and a rotary fan therein, said fan comprising a disk and a plurality of blades on one side thereof radiating outwardly to the periphery of the disk, the side wall of said fan casing adjacent said blades being recessed and having anchored therein a lining plate close to which said fan blades sweep, and a nozzle communicating with said fan casing through an opening in said lining plate.

2. In a suction cleaner, the combination of a fan casing, and a rotary fan comprising a disk and a plurality of blades on one side thereof radiating outwardly to the periphery of the disk, the side wall of said fan casing adjacent said blades being recessed and having anchored therein a lining plate close to which said fan blades sweep and a nozzle communicating with said fan casing through a central axial opening in said lining plate.

3. In a suction cleaner, the combination of a fan casing and a rotary fan therein comprising a disk and a plurality of blades radiating out from one side thereof, the side wall of said fan casing adjacent said fan blades being recessed and having anchored therein a lining plate, a forwardly projecting and downwardly extending nozzle, said nozzle comprising a tubular member connected between the downwardly extending portion of said nozzle and said fan casing and leading through an opening in said lining plate.

4. In a suction cleaner, the combination of a fan casing and a rotary fan therein comprising a disk and a plurality of blades radiating out from one side thereof, the wall of said fan casing adjacent said fan blades being recessed and having anchored therein a lining plate, a forwardly projecting and downwardly extending nozzle, said nozzle comprising a tubular member connected between the downwardly extending portion of said nozzle and said fan casing and leading through a central axial opening in said lining plate.

5. In a suction cleaner, the combination of a motor casing and a fan casing, said casings having co-operating cylindrical flanges for securing the two casings together, a rotary fan in said fan casing having fan blades, the forward side of said fan casing being recessed and having anchored therein an annular plate close to which said fan blades sweep, a nozzle projecting forwardly of said fan casing and comprising a tubular member in register with the annular plate and in axial alinement with said casings, said member connecting the downwardly ex-

tending portion of said nozzle with said fan casing.

6. In a suction cleaner, the combination of a motor casing and a fan casing, a rotary fan in said fan casing comprising a disk and fan blades on the forward side thereof, the forward side wall of said fan casing having a central axial opening therein and having anchored around said opening an annular plate close to which said fan blades sweep, a nozzle communicating with said fan casing, said nozzle comprising a tubular member in register with said opening, and in axial alinement with said casings, said member forming a communicating channel between said fan casing and the downwardly extending portion of said nozzle.

7. In a suction cleaner, the combination of a motor casing and a fan casing, said fan casing having projecting forwardly thereof a downwardly extending nozzle, a tubular member forming a central axial communicating channel between said nozzle and said fan casing, and a rotary fan in said fan casing having a disk on its rearward side and having extending forwardly from said disk a plurality of fan blades, the side wall

of the fan casing adjacent said fan blades and surrounding said communicating channel being recessed and having anchored 30 therein a flat lining plate for the purpose described.

8. In a suction cleaner, the combination of a motor casing and a fan casing, said fan casing having projecting forwardly thereof a downwardly extending nozzle, said nozzle comprising rear and forward walls, a tubular member forming a central axial communicating channel between said nozzle and said fan casing, a rotary fan in said 40 fan casing having a disk on its rearward side and having extending forwardly from said disk a plurality of fan blades, the side wall of the fan casing adjacent said fan blades and surrounding said communicating 45 channel being recessed and having anchored therein a flat lining plate, the forward wall of said nozzle having an opening in alinement with said tubular member, and a closing plate therefor, for the purpose de- 50 scribed.

In testimony whereof I hereunto affix my signature.

ELROY C. ROBERTSON.
